SLIDING JAW WRENCH WITH SLIDING RACK CATCH

Rudolph Steinacher, New York, N. Y.

Application June 12, 1944, Serial No. 539,923

1 Claim. (Cl. 81—145)

1

The present invention relates to sliding jaw wrenches, and particularly to the construction of sliding jaw wrenches which are relatively large and strong and are adapted for heavy duty service.

The general object of the invention is to provide a wrench of the type mentioned which is relatively simple and inexpensive in construction, and which comprises novel and effective means for releasably locking two wrench jaws together with a work receiving space between them which may be varied by increments, such, for example, as of one millimeter each, which are sufficiently small for substantially all practical purposes served by such a wrench.

My invention is characterized in particular by its inclusion of jaw locking means comprising side by side, transverse locking spaces or grooves formed in the wrench shank to one end of which one of said jaws is attached, said spaces being similarly spaced apart longitudinally of the shank and being similar in width. The locking means also comprise side by side locking spaces or grooves parallel to the first mentioned spaces which are formed in a sliding member which carries the second wrench jaw and which is mounted on said shank for movement longitudinally of the latter to vary the size of the work receiving space between the two jaws. The locking spaces formed in said member are similar in width to the first mentioned locking spaces and are uniformly spaced in the longitudinal direction of the shank. The distance between two adjacent locking spaces formed in the member differs from the distance between each two adjacent shank locking spaces by a distance substantially smaller than either of the previously mentioned distances. An individual locking member, or bolt, is mounted in each of the locking spaces formed in said member. Except when restrained by a control or key element, each locking member is adapted to extend into a shank space in direct juxtaposition with the space of said body in which the locking member is mounted so as to thereby lock the sliding member against movement relative to the shank in the longitudinal direction of the latter.

In the preferred form of the invention, each of the locking members is biased for movement in the direction to enter a juxtaposed shank locking space and a key element is mounted in the wrench for adjustment relative to the sliding member between one position in which it holds each locking member against movement into a juxtaposed shank locking space, and a second

2

position in which it does not interfere with such locking member movement.

The above described locking space arrangement permits of a sort of vernier adjustment of the width of the work receiving space between the two wrench jaws in increments each equal to the difference between the distance separating adjacent shank locking spaces and the distance separating adjacent locking spaces in the sliding member.

The various features of novelty which characterize my invention are pointed out with particularity in the claims annexed to and forming a part of this specification. For a better understanding of the invention, however, its advantages and specific objects attained by its use, reference should be had to the accompanying drawings and descriptive matter in which I have illustrated and described preferred embodiments of the invention.

Of the drawings:

Fig. 1 is an elevation of a sliding jaw wrench;

Fig. 2 is a partial longitudinal section taken on the line 2—2 of Fig. 1;

Fig. 3 is a transverse section taken on the line 3—3 of Fig. 2; and

Fig. 4 is a transverse section on the line 4—4 of Fig. 2.

In the preferred form of the invention shown in the drawings, A represents the wrench shank to one end of which the wrench jaw B, commonly referred to as the stationary jaw, is rigidly attached. The second, or sliding jaw C of the wrench, is connected to and form part of a sliding member D mounted on the shank A for sliding adjustment in the longitudinal direction of the latter. As shown, the member D is in the form of a flattened tubular body or sleeve, and its bore is shaped to provide a suitably close sliding fit with a shank A which extends through it. A multiplicity of side by side, transverse grooves or locking spaces E are formed in one side of the shank A. The spaces E are all of the same width and are uniformly spaced longitudinally of the shank, and each is adapted to receive one or another of a plurality of movable locking or bolt members F mounted in the sliding member D in appropriate adjustments of the latter longitudinally of the shank A.

Each of the bolt members F in the form shown is in the form of a bar rectangular in cross section and extending transversely to the length of the shank A and parallel to the side of the shank in which the spaces E are formed. Each locking member F is mounted in a corresponding groove

or slot-like locking space G formed in the sliding member E. The spaces G are similar in width to the shank spaces E, and ordinarily the locking members F are only sufficiently smaller in width than the spaces E and G to permit easy movement of each locking member from its jaw locking position shown in Fig. 4, into its jaw releasing position shown in Fig. 3.

The locking spaces G are uniformly spaced apart in the longitudinal direction of the shank A, but the distance between each two adjacent spaces G is slightly greater than the distance between each two adjacent grooves E as is clearly shown in Fig. 2. While the relative spacing of the two sets of grooves and the dimensions of a wrench embodying the present invention may vary widely as conditions make desirable, it is noted, by way of example, that in one design of wrench shaped and proportioned as shown in the drawings and intended for heavy duty service, the maximum operative distance between the two wrench jaws B and C is slightly more than 90 millimeters, the width of each of the spaces E and G is 3 millimeters, the spacing distance between each two adjacent shank locking spaces E is 5 millimeters, and the spacing distance between each two sliding member locking spaces F is 6 millimeters.

Each of the locking bolts F is shown as biased by an individual bent spring I for movement toward its jaw locking position shown in Fig. 3. As shown, each spring I is of arc shape with its concave side adjacent the corresponding locking member which is engaged adjacent its ends by the corresponding ends of the spring. The central or crown portion of the convex side of each spring I engages the corresponding portion of a retaining strip H. The latter may be removably or permanently attached to the member D and extends longitudinally of the latter over all of the spaces E. When, as is usual, the member H is formed separately from the member E, the spaces G may well be in the form of slots extending through one side wall of the passage through the tubular member E. To facilitate their formation, each of the spaces E may well be formed with a rounded bottom as shown.

To hold each of the locking members F out of engagement with the shank A, when adjustment of the sleeve D on the shank A is desirable, I have provided the wrench shown with a manually adjustable key J in the form of a toothed or rack bar. The key is mounted in the sliding member D so as to share the general movements of the latter longitudinally of the shank A, but is permitted a small adjustment relative to the member E in the longitudinal direction of the shank. As shown, the tips of teeth J' of the bar J extend into a guideway formed by aligned, spaced apart grooves KE formed in the different spacing walls between the different spaces G. The untoothed edge of the key J is received in a groove KA formed in the adjacent side of the shank A, and shown as extending between the jaw B and the remote end of the shank. The key teeth J' correspond in number and spacing to the locking spaces G of the sliding member D. When the key J is in its advanced position shown in Fig. 2, it does not interfere with the movement of any one of the locking members F into the jaw locking position in which it extends into a shank locking space E in directly juxtaposed relation. When the key J is moved to the left from its position in Fig. 2 for a distance equal to the tooth spacing distance between its teeth J', one or another of

the teeth J' will be in engagement with each locking member F and will hold the latter clear of the shank A.

The wrench is preferably provided with readily accessible and operable means for adjusting the key member J. The means for the purpose shown, comprises an uprising pin L carried by the bar J and extending into an inclined cam slot M' formed in an adjusting member M. The latter is mounted on an elongated slot N formed in the member D and extending transversely to the length of the shank A. As the member M is moved from the end portion of the slot N in which it is shown in Fig. 1, to the opposite end portion of that slot, the wall of the groove M' cams the pin L to the right as seen in Fig. 1 with the result of moving the key bar J from its position shown in Fig. 2 into the position in which its teeth J' prevent the different locking members from passing into engagement with the shank A, so that the sliding member D is then free for longitudinal adjustment along the shank A.

As shown, no locking spaces or grooves E are formed in a handle portion of the shank A adjacent the end of the latter remote from the jaw B, and the normal movement of the jaw C away from the jaw B is limited by a retaining member P removably secured in and projecting up out of the groove E most remote from the jaw B. The member P forms a stop engaged by the adjacent end of the sliding member D when the latter is adjusted to provide the maximum work space width between the two wrench jaws B and C. As shown, the member P is detachably secured in place by means of a headed tubular retaining member P' internally threaded to engage a threaded stem portion of the member P.

As will be apparent to those skilled in the art, the wrench construction illustrated is relatively simple and inexpensive in construction, and when its parts are suitably proportioned and formed of suitable metal, the wrench is well adapted to withstand the stresses and wear incident to heavy duty wrench operations. For such operations a lever handle extension may be connected from time to time in customary manner to the free end of the shank A. The wrench may be quickly adjusted to vary the width of the work receiving space between the jaws B and C. All that is required to effect such adjustment is the movement of the member M from one end to the other of the slot N to release the previously established locking connection between the member D and shank A, the movement of the member D longitudinally of the shank A, and the return of the member M to the end of the slot N from which it had previously been moved. As will be apparent, also, with a wrench having the dimensions given above by way of example, the member D may be locked to the shank A in each of a multiplicity of different positions differing from one another in the direction of the length of the shaft by increments of 1 millimeter each.

While in accordance with the provisions of the statutes, I have illustrated and described the best forms of embodiments of my invention now known to me, it will be apparent to those skilled in the art that changes may be made in the forms of the apparatus disclosed without departing from the spirit of my invention as set forth in the appended claim, and that in some cases certain features of my invention may be used to advantage without a corresponding use of other features.

Having now described my invention, what I

claim as new and desire to secure by Letters Patent, is:

A sliding jaw wrench comprising a jaw and a bar-like shank to one end of which said jaw is attached, a second jaw, a sliding member mounted on said shank for sliding movement longitudinally of the latter and to one end of which said second jaw is attached, said shank being oblong in cross section and slotted at one of its wider sides to form elongated locking spaces transverse to the length of the shank and said jaws having working faces extending away from the shank at one of the narrower sides thereof, said locking spaces being similar in width and similarly spaced apart in the longitudinal direction of the shank and said sliding member comprising side by side locking spaces parallel to and similar in width to said shank spaces, said sliding member spaces being similarly spaced apart in the longitudinal direction of said shank and the distance between each two adjacent shank spaces differing from the distance between two adjacent sliding member spaces by a distance substantially smaller than either of the previously mentioned distances, means for releasably securing said sliding member to said shank in different adjustments longitudinally of the latter comprising locking members mounted in and elongated in the direction of the length of the locking spaces of said sliding member and each movable therein between a jaw locking position in which it extends into any directly juxtaposed shank lock space, a jaw releasing position in which it is displaced lat-

erally from said shank locking spaces, said shank being formed with a longitudinally extending slot open at the same side of the shank as the first mentioned slots and of a width substantially smaller than the length of each of the first mentioned slots and intersecting the first mentioned slots substantially midway between their ends, and a bar slidably mounted in said longitudinal slot, and having longitudinally spaced projections and being longitudinally movable in said longitudinal slot between one position in which each of said projections is adapted to maintain a corresponding one of said locking members in its jaw releasing position, and a second position in which it does not interfere with the movement of any of said locking members into its jaw locking position.
